UNITED STATES PATENT OFFICE

ROGER TULL, OF LOS ANGELES, CALIFORNIA, ASSIGNOR TO WESTERN LITHOGRAPH COMPANY, OF LOS ANGELES, CALIFORNIA, A CORPORATION OF CALIFORNIA

METHOD OF MAKING CLOTH STENCILS FOR MULTICOLOR WORK

Application filed February 11, 1928. Serial No. 253,764.

This invention relates to methods of making cloth stencils for multi-color work, and, more especially, to that type of stencil that employs bolting cloth, or equivalent fabric, through which paint is forced onto a sheet of paper or other surface that is to receive the print.

An object of the invention is to improve the method disclosed in my former Patent No. 1,622,747 dated March 29, 1927.

This invention makes it possible to prepare stencils photographically from an original in which some of the colors to be reproduced have photographic color values that are not markedly different.

This method is especially useful in the reproduction of crayon originals as by it the crayon effect is reproduced.

The accompanying drawings illustrate some of the operations of the new method and the product resulting from the same.

Fig. 1 represents a colored original that is to be reproduced, the different colors being only indicated in black and white.

Fig. 2 represents a negative plate photographed from the original in Fig. 1.

Fig. 3 represents a positive plate made from either the original shown in Fig. 1 or the negative shown in Fig. 2.

Fig. 4 represents a print on sensitized screen fabric from the positive shown in Fig. 3.

Fig. 5 represents a print on sensitized screen fabric from the negative shown in Fig. 2.

Fig. 6 represents a stencil resulting from blocking out the print shown in Fig. 4.

Fig. 7 represents a stencil resulting from blocking out the print shown in Fig. 5.

Fig. 8 represents a print made by using the stencil shown in Fig. 6.

Fig. 9 represents the print shown in Fig. 8 after it has received an impression by use of the stencil shown in Fig. 7.

Fig. 10 represents the completed reproduction, showing all the colors contained in the original, said colors being simply indicated in black and white.

To perform the method of this invention, a colored original, such as that represented

in Fig. 1, is photographed on a sensitized plate, in a manner well understood in the art pertaining to photography and the result is a negative such as that indicated in Fig. 2. Preferably, to get as strong color contrast values as is possible the photographic negative will be made by the use of the wellknown color screen or screens or, at least, it is advisable to employ a light sensitive plate that is panchromatic.

After this operation a photographic positive will be prepared of the same subject and said positive may be made by photographing through the negative in Fig. 2 upon a sensitized plate which, also, is preferably panchromatic. This positive is represented in Fig. 3.

The next operation is to make photographic prints from the negative and positive on sensitized screen fabric such, for example, as bolting cloth which is usually employed where paint is to be forced through it for making prints. The term "bolting" wherever employed in this description defines any fabric suitable for use as a stencil screen.

The photographic prints mentioned above may be made as follows: No. 14XX bolting cloth is stretched over the edge of a wooden frame and the cloth thus stretched is taken to a dark room, and a camel hair brush is employed for covering the bolting cloth on the outer side with a solution made as follows: 90 grains of bichromate of ammonia is dissolved in 5 ounces of distilled water and this mixture will be identified as mixture A. 2 ounces of liquid glue are mixed with the white of one egg or albumen egg merck, and this will be identified as mixture B. Mixtures A and B thus produced will then be thoroughly stirred together and 10 drops of aqua ammonia added and this mixture will be identified as mixture C. Metal must not touch the solution nor should it be exposed to any except red light. After the sensitizer thus made has been applied to the bolting cloth and has dried, the drying taking about an hour, the sensitized cloth is ready for printing from the negative.

For printing, the negative will be placed in close contact with the sensitized bolting

cloth and then exposed, say for 5 minutes in front of two 500 watt lamps. After thus exposing, the negative is removed and the bolting cloth thus exposed is washed under 5 running water to wash out the glue solution. Compressed air will be used to free the clear portions of the bolting cloth of the water. Those portions of the sensitizer rendered insoluble in water by the action of light will 10 not be washed off.

After this treatment, the printed bolting cloth will be placed in the sunlight until the sensitizer that remains hardens. This takes about 10 minutes. If there is no sunlight, it 15 should dry in a place free from dust.

The print resulting from printing through the positive shown in Fig. 3 is indicated in Fig. 4 and the print resulting from printing through the negative shown in Fig. 2 is indicated in Fig. 5. For clearness of description these prints on fabric will be termed herein screen prints. It is to be understood that there will be one screen print made for each color that is to be reproduced. For example, 20 assuming that the original is in twelve colors, six screen prints will be made from the negative and six from the positive. By having prints made from both negative and positive plates, the blocking out of the color areas that 25 it is not desired that the paint pass through is facilitated as will be made clear hereinafter. The actinic action of the light, on those portions of the sensitizer that are exposed to the light rays passing through the plates, hardens 30 said portions and thus photographically blocks out certain areas on said plate. Thus, it will be seen, that the photographically blocked out areas on the positive prints are those areas that correspond to the colors having 35 the lesser actinic values in the original; and that the photographically blocked out areas on the negative prints are those areas that correspond to the colors having the greater actinic values in the original. Thus 40 the positive prints will have clear portions so that paint will pass through to render the colors of relatively high actinic value, while the negative prints will have clear portions for the passage of paint to render the colors 45 that have relatively low actinic value. Two such stencils are represented in Figs. 6 and 7, that in Fig. 6 representing the stencil produced by blocking out the stencil print 4 and that shown in Fig. 7 being the result of blocking 50 out the print shown in Fig. 5. It is to be understood that if the printing is to be done in twelve colors it will be necessary to block out on twelve screen prints so as to produce twelve stencils since some of these stencils 55 will be the result of blocking out on the positive prints and some from blocking out on the negative prints. The advantage of making prints from both positive and negative plates 60 will now be seen for, in order for paint to 65 pass through any given color area, said area

must have its mesh or pores open. To obtain the open pores for some colors, prints from the negative are required whereas to obtain open pores for other colors, prints from the positive plate are necessary. This will be 70 readily understood by referring to Figs. 4 and 5 of the drawings. In Fig. 4 which represents a print from the positive plate, the area 11 is open for the passage of paint of one color and in Fig. 5 which represents a 75 print from the negative plate, the corresponding area 11a is closed so that paint of a different color cannot pass through said area. Another reason for employing prints from both positive and negative plates is that the 80 artist can the more readily distinguish between certain colors in the blocking out of the prints for producing stencils for the different colors.

After the screens have been prepared in 85 this manner, they will be treated with lacquer mixed with No. 206 Zapon blue and No. 16 Zapon thinner, or other suitable nitro-cellulose products. This solution is applied on one 90 side of the screen with a large brush and, at the same time, the other side of said screen is rubbed with a soft rag.

The stencils having been produced as above described concludes the new method. The stencils will be employed in a manner well 95 understood in this art by forcing wet paint through the open area of one of the stencils onto the surface that is to receive it and, after the paint on said surface is sufficiently dry, another stencil for a different color will 100 be laid over the printing surface and a different color of paint pressed through the second stencil upon said surface or/and upon a portion of the first printed color. Thus, all of the stencils for the different colors will be 105 used successively and the resulting product is shown in Fig. 10 which is virtually a duplicate of the original shown in Fig. 1.

From the foregoing it will be readily understood that I have discovered how to reproduce a crayon or pastel original that is 110 in many colors so as to obtain an effect that, at a slight distance, cannot be distinguished from crayon or pastel work. It is practically impossible to show in pen and ink drawings the peculiar and extremely pleasing effects that can be produced by this method to resemble crayon pictures. However it will 115 be greatly appreciated by those skilled in the art that the simulated strokes of the crayon that can be obtained by this method the more closely resemble crayon or pastel strokes on crayon paper because of the more or less jagged effect secured by forcing the paint through bolting cloth, a form of stencil that 120 is now widely used.

I claim:

The method of making cloth stencils for multi-color work consisting in making a photographic positive plate and negative plate 125

from the colored original that is to be reproduced, making photographic prints on sensitized bolting cloth from the positive and negative plates, blocking out on the print
5 from the positive plate an area that is to be impervious to paint and that corresponds to one of the colors that photographed dark on the positive plate, and blocking out on the print from the negative plate an area that is
10 to be impervious to paint and that corresponds to one of the colors that photographed dark on the negative plate.

Signed at Los Angeles, California, this 23
day of January, 1928.

15 ROGER TULL.
